CLAIM

The ornamental design for a control stabilizer, as shown.

DESCRIPTION

FIG. 1 is an environmental, perspective view thereof;

FIG. 2 is an enlarged, perspective view thereof;

FIG. 3 is a bottom perspective view thereof; and,

FIG. 4 is a sectional view taken along line 4—4 of FIG. 1.

The broken line showing of a foot and a pedal is included for the purpose of illustrating environment and forms no part of the claimed design.
